ALBERT H. STEBBINS, OF LOS ANGELES, CALIFORNIA

SLUICE CONCENTRATOR

Application filed April 28, 1927. Serial No. 187,372.

This invention relates to a novel form of sluice in which water bearing the materials to be separated is conducted through a pipe to effect a gravity separation of the materials.

Sluices or sluice boxes as commonly employed heretofore to separate ore have the form of a relatively long trough through which the ore is carried by a stream of water.

10 Riffles or projections are provided in the bottom of the trough to catch the heavier particles that settle to the bottom, and the flow through the sluice box is periodically arrested in order that the heavier particles 15 or values collected in the trough may be removed.

In accordance with the present invention water bearing the materials to be separated is conducted through a pipe which may be 20 called a "sluice pipe" and the construction is such that a gravity separation of the material conveyed by the stream is effected. In this construction the heavier particles are not caught in pockets or arrested by 25 riffles as has been customary in the sluice box, employed heretofore, but the materials that differ in specific gravity arrange themselves at different elevations within the flowing stream, and as a result the desired separation 30 of the materials may be effected by drawing off different horizontal portions or sections of the stream at different elevations from the lower wall of the pipe. The water is preferably supplied to the sluice pipe 35 under sufficient head pressure to keep the pipe full of water and to promote the flow of water through the pipe at sufficient speed to prevent the heavier particles from settling upon the lower side of the pipe.

40 One important feature of the present invention, therefore, resides in a sluice pipe through which water bearing the materials to be separated is conducted so that a gravity separation of the materials takes place within 45 the stream, and in means for removing from the pipe through differently elevated outlets the water and materials traveling in different horizontal planes of the stream.

Another feature of the invention resides 50 in the novel construction of the sluice pipe

whereby different portions of the pipe are given different configurations in cross-section to promote gravity separation of the materials within the stream of water.

Still another feature of the invention resides in the construction whereby jets of water or other fluid are forced upwardly through the lower wall of the sluice pipe to promote separation of the materials.

Other features of the invention and novel 60 combination of parts in addition to the above will be hereinafter described in connection with the accompanying drawings which illustrate good practical forms of the invention.

65 In the drawings:—

Fig. 1 is a perspective view of a sluice concentrator constructed in accordance with the present invention;

Fig. 2 is a vertical sectional view through 70 the discharge end portion of the sluice pipe of Fig. 1;

Figs. 3, 4, 5 and 6 are sectional views taken on the lines 3—3; 4—4; 5—5 and 6—6 respectively of Fig. 1;

Fig. 7 is a vertical sectional view through 75 a modified type of sluice concentrator;

Fig. 8 is an end view of the discharge end portion of Fig. 1;

Figs. 9 and 10 are sectional views taken 80 on the lines 9—9 and 10—10 respectively of Fig. 7; and

Fig. 11 is a vertical sectional view through 85 the discharge end portion of a further modified type of sluice concentrator.

In accordance with the present invention the separation of the materials being treated is effected within the sluice pipe 10 as they are carried through this pipe by a stream of water. The size, shape and length 90 of the pipe 10 may be varied as desired or as may be necessary to meet the particular requirements of materials being treated, but in most cases the pipe should be relatively long to allow the materials suspended in the water sufficient time to work either up or down within the stream in accordance with 95 their differences in specific gravity.

In the construction shown the pipe 10 has a flattened construction near its material 100

receiving end as will be apparent from Figs. 1 and 3, and the shape of the pipe is gradually changed in the direction of its length, as will be apparent from the sectional views of Fig. 1. The discharge end portion of the pipe 10 is shown as tall and narrow in cross-section. The pipe 10 is given the flattened construction shown near its feed end in order that the heavier particles will need to settle only a short distance to reach the lower wall of the tube, and this pipe is given the tall narrow construction near its discharge end shown in Fig. 6, to promote the collection of the materials in different elevated positions within the stream of water, and also to facilitate the removal of the water from the pipe through discharge openings arranged at different elevations from the bottom wall of the pipe.

20 The ore which has been comminuted or crushed and the water may be mixed by any suitable means before they are delivered to the pipe 10, or they may be conveyed separately to the feed hopper 11 provided at 25 the upper end of the feed pipe 12 that is attached to the flattened end of the sluice pipe 10. In the construction shown the water is supplied to the feed hopper 11 by the pipe 13 and the ore or other materials to be separated is delivered to the feed hopper by the pipe 14.

It may be desirable to vary the inclination of the pipe 10 to increase or decrease the water pressure therein and also to vary the 35 tendency of the particles to settle in the pipe. The hopper 11 is therefore shown as having the trunnions 15 journaled in bearing blocks 16 supported by the posts 17. The opposite end of the pipe 10 may be adjustably supported by the suspension rods 18 secured to the beam 19 by the adjustable nuts 20.

From the construction so far described it will be seen that the materials undergo a 45 gravity separation as they travel with the water lengthwise of the pipe 10 and that the heavier particles will collect in that portion of the stream lying near the lower side of the pipe, while the lighter particles will remain suspended in the stream above the heavier particles or concentrates. As a result of this gravity separation of the materials conveyed by the stream, the desired concentration of the materials may be effected 50 by removing from the pipe 10 through different outlets the graded materials traveling within the pipe at different elevations from the lower side thereof.

The means for removing from the pipe 60 the portions of the stream in which the different materials are carried may be variously constructed and one good form of means to this end is shown in Fig. 2 wherein the discharge portion of the pipe is provided 65 with the transversely extending partitions

21 arranged to form the discharge passages 22. The water and the heavy materials traveling near the lower wall 23 of the pipe will obviously enter the lowermost passage 22 while the slightly lighter particles will enter the next higher passage 22, and the lightest and finest particles will enter the passage lying near the upper wall 24 of the pipe. The water and materials that enter the different passages 22 pass downwardly through the discharge spouts 25 into the transversely extending pipes 26 which discharge into separate settling tanks 27. The pipes 26 are preferably connected to the tanks 27 by the flexible pipes 29 each of which is connected to a pipe 30 for one of the tanks. The flexible connections 29 permit the vertical adjustment of the discharge end of the pipe 10 above mentioned. As a result of the sluice construction de- 85 scribed the concentrates or values will be separated from the lighter materials and will collect in the concentrate settling tank 27 lying at the right-hand end of the series of tanks shown in Fig. 1, and the lighter 90 materials will collect in accordance with their size and specific gravity in the other tanks 27. The lightest and finest particles will collect in the tank at the left-hand end of the series shown in Fig. 1.

It may be desirable to control the volume of water discharged through each of the 100 passages 22, but the means for controlling this flow should be so constructed that the discharge passages will not become clogged through the accumulation of the materials therein. This is accomplished in accordance with the present invention by providing each passage with a discharge spout which is large enough to carry the major portion of the water that is delivered to the spout by its passage 22. The remaining portion of the water that enters a particular passage 22 is conducted to the pipe 26 through a by-pass pipe 31 provided with a regulating valve 32, and the upper end of each by-pass pipe is located to one side of the main passage within a spout 25 and is provided with a guard plate 33 which prevents the muddy deposits from entering a pipe 31 to clog the same. In this manner the volume of water passing through a conduit 22 may be controlled to a certain degree by adjusting the valve 32 while danger of the parts becoming 115 clogged is prevented.

In some cases it may be desirable to promote the separation of the materials by forcing jets of water upwardly through the lower side of the sluice pipe 10, and means to this end is shown in Fig. 7 wherein the lower side of the pipe 10 is provided with apertures 33 through which jets of water are forced from a pressure chamber 34 formed by providing the receptacle 35 at the lower side of the pipe 10. Water under pressure is sup- 125 130

plied to the receptacle 35 by a pipe 36 leading from the supply tank 37. Should air accumulate in the pipe 10 it may escape therefrom through the vent pipe 38 which is sufficiently tall to prevent water from escaping from its upper end.

In Fig. 11 is shown a modified construction in which the lower portion of the sluice pipe 10 is made longer than the upper portion thereof and the partitions 39 are arranged in the form of steps as shown so that the lighter materials traveling near the upper wall of the pipe 10 will be the first to escape through the passage 40 and pipe 41 into a settling tank 42 and the heavier particles will be the last to escape from the pipe 10.

From the foregoing it will be seen that the separation of the material may be carried on continuously and that it is unnecessary to stop the operation from time to time and remove the values as is customary in the trough type of sluice box. Furthermore, the materials are separated in a number of different grades comprising values, middlings and tailings. The size of the pipe 10 may be decreased slightly toward its discharge end to cause the water to travel at an uniform speed through the length of the pipe and the separation of the material effected will be primarily in accordance with the differences in specific gravity but to some degree in accordance with the size of the particles.

What is claimed is:—

1. A sluice concentrator, comprising in combination, a sluice pipe closed from the point of feed to the points of discharge and adapted to have a stream of water bearing the materials to be separated forced therethrough under a maintained head pressure and constructed to promote a gravity stratification of the materials within the flowing stream so that materials differing in specific gravity will remain suspended in different vertically disposed portions of the stream moving through the pipe, settling receptacles, and partitions extending across said pipe near its discharge end and arranged one above the other to form a series of discharge conduits leading to said receptacles and each conduit being adapted to carry off at an undiminished rate of flow the entire volume of water that enters the space between the adjacent partitions of a conduit to thereby avoid intermingling of the materials of the different sections of the stream adjacent the entrance to the conduits.

2. A sluice concentrator, comprising in combination, a sluice pipe closed from the point of feed to the points of discharge and adapted to have a stream of water bearing the materials to be separated forced therethrough under a maintained head pressure and constructed to promote a gravity stratification of the materials within the flowing

stream so that materials differing in specific gravity will remain suspended in different vertically disposed portions of the stream moving through the pipe, settling receptacles, means for directing jets of water upwardly through the lower wall of said pipe to promote separation of the materials, and partitions extending across said pipe near its discharge end and arranged one above the other to form a series of discharge conduits leading to said receptacles and each conduit being adapted to carry off at an undiminished rate of flow the entire volume of water that enters the space between the adjacent partitions of a conduit to thereby avoid intermingling of the materials of the different sections of the stream adjacent the entrance to the conduits.

In testimony whereof, I have signed my name to this specification.

ALBERT H. STEBBINS.
